UNITED STATES PATENT OFFICE.

AUSTIN F. JACKSON, OF TAUNTON, MASSACHUSETTS, ASSIGNOR TO THE REED & BARTON CORPORATION, OF SAME PLACE.

DESIGN FOR A BRUSH OR MIRROR BACK.

SPECIFICATION forming part of Design No. 22,341, dated April 11, 1893.

Application filed March 15, 1893. Serial No. 466,143. Term of patent 7 years.

To all whom it may concern:

Be it known that I, AUSTIN F. JACKSON, a citizen of the United States, residing at Taunton, in the county of Bristol and State of Massachusetts, have invented and produced a new and original Design for the Backs of Brushes, Mirrors, and Kindred Articles, of which the following is a specification, reference being had to the accompanying drawing, in which the figure is a plan view of a back showing my design.

The leading feature of my design consists in the edge bead like representation and the floral sprays.

A, is the body or main portion of the back and B is the handle. At the top of the portion A, I produce at each side a series of bead like representations *a* meeting at the middle of the top of the brush and extending thence to the sides and about half way down the sides of the body where they merge in a single side bead *a'* from which they appear to spring. These side beads *a'* extend along

the side of the body and thence along the edges of the handle until they meet at the 25 extremity of the handle, a floral spray *a²* leading upward from their juncture as shown. At intervals the beads are produced in series as represented at *a³* and *a⁴*. At the middle point of the top or the back or from the juncture of the opposite series of beads *a a* is produced a floral spray C, while sprays C' C² are produced where the beads *a* merge into the bead *a' a'*. Within the opposite corners of the lower end of the main portion A, are produced the convoluted scrolls D, between which extend the ribbon like representations E from which project the floral representations F, and G.

What I claim is—

The design for a brush back, mirror back or similar article, herein shown and described.

AUSTIN F. JACKSON.
